UNITED STATES PATENT OFFICE.

JAMES M. MONTGOMERY, OF WINFIELD, KANSAS, ASSIGNOR TO THE ARCUS TICKET CO., OF CHICAGO, ILLINOIS, A CORPORATION OF ILLINOIS.

TICKET-ROLL CLIP.

Application filed February 21, 1922. Serial No. 538,176.

To all whom it may concern:

Be it known that I, JAMES M. MONTGOMERY, citizen of the United States, residing at Winfield, in the county of Cowley and State of Kansas, have invented certain new and useful Improvements in Ticket-Roll Clips, of which the following is a specification.

This invention relates to a clip designed to hold the loose ends of ticket strip rolls such as used at amusement parks, carnival, theatres, etc.

An object of the invention is to provide means for keeping the roll intact and preventing the end ticket from unrolling or becoming torn off and lost when the roll is carried from place to place.

An additional object is to provide a clip of the character specified which is compact and adjustable and which can be readily applied to or detached from the tickets of an ordinary ticket strip, being adjustable for the different width ticket strips.

A further object of the invention is to provide a clip that is simple in construction, strong, and durable and which can be manufactured at a low cost.

Various other objects and advantages of the invention will become apparent from a consideration of the following description.

30 In the drawings:

Figure 1 illustrates a section of the ticket roll with the clip applied thereto.

Figure 2 is a top plan view thereof.

Figure 3 is a vertical cross section taken 35 on line 3—3 of Figure 2.

Figure 4 is a plan view of one part of the clip, and,

Figure 5 is a plan view of the other part of the clip.

40 Practically all tickets sold at amusement parks, carnivals, theatres, et cetera, are put up in rolled strip form and numbered consecutively, the cashier or ticket seller tearing them off the strip as sold. At the close 45 of the performance the remaining tickets, in roll form, are deposited in the office for safe keeping, as each one represents the admission price charged to each person entering and the amount of business done is determined by referring to the consecutive 50 numbers appearing on the tickets. When used for amusement parks and carnivals, the rolls are often carried quite a distance to the wagon and the ticket strip unrolls and

55 tickets are frequently torn off and lost, there being nothing to keep the loose ends in place. This clip is designed and adapted to be applied to the roll to prevent the tickets at the free end of the ticket strip being torn or detached and lost, as illustrated in 60 the drawings. A section of the usual ticket roll is indicated at 10 and the loose end of the strip at 11.

The clip is made of thin sheet metal, such as tin, steel, or brass and comprises two 65 plates 12 and 16 (Figures 4 and 5). The plate 12 has marginal end portions 13 and 14, adapted to be folded on the dotted lines so as to provide guide ways on the under 70 face of the side margins of the plate for the plate 16, for the purpose presently to be described.

One end of the plate 12 is formed with an extension 15 which is folded along the dotted line shown to extend downwardly 75 from the plate to constitute a guide flange to overlap a side of the ticket roll, and said flange is provided with a centrally disposed spur 20'. The plate 16 is shorter than the plate 12 and is adapted to be folded along 80 the dotted line, shown in Figure 5, so as to provide a guide flange 17 to overlap one side of the ticket roll, in the same manner as the flange 15. Said flange 17 is formed with a centrally disposed spur 20'. The 85 plate 16 is adapted to slide back and forth under the plate 12 in the guide ways formed by the inwardly turned portions 13 and 14, and is provided with an upwardly projecting tongue 18 which is slidable in a slot 19 90 formed in the plate 12. Said tongue 18 serves as a stop for limiting the sliding adjustment of the clip. The said spurs 20', 20' are adapted to be bent inwardly from 95 the free margins of the flanges 15 and 17 when the plates are assembled one over the other in the manner shown in Figure 3 so as to penetrate spaces between the strip turns and thus serve as means to hold the clip on the periphery of the roll.

100 In the use of the assembled clip, it is fitted snugly down over the roll at the point where the loose ticket strip end 11 issues from the roll. The clip is thus applied to the roll at a time when the clip members 105 are adjusted with their spurs 20', 20' spread a distance apart, greater than the width of the ticket strip, permitted by the tongue

and slot connection described. The clip is then clamped in place over the last ticket of the strip, representing the next ticket to be dispensed by pressing the flanged ends 5 of the clip between the thumb and first finger until the spurs 20' penetrate the sides of the roll, as shown in Figure 3. The clip will thus be held securely in place and the ticket strip will be prevented from unrolling. The tongue and slot connection adapt the clip to ticket strips of different widths and the tongue 18, which is struck up from the plate 16, can be engaged by the finger to spread said plates to detach the clip from 15 the roll.

From the foregoing it is believed that the advantages and novel features of the invention will be readily understood and, therefore, further detailed description is deemed 20 unnecessary.

I claim as my invention:

1. The combination of two thin, generally rectangular, sheet metal plates lying one over the other and of like dimensions in 25 their superposed parts, both said plates having relatively deep, inwardly turned holding flanges, equipped with spurs which are bent inwardly from said flanges towards each other, one of said plates being formed 30 at its margins with guide flanges for engagement with the margins of the other plate.

2. The combination of two thin, generally rectangular, sheet metal plates lying 35 one over the other and of like dimensions in their superposed parts, both said plates having relatively deep, inwardly turned

holding flanges, equipped with spurs which are bent inwardly from said flanges towards each other, one of said plates being formed 40 at its margins with guide flanges for engagement with the margins of the other plate, and one of said plates being slotted to receive a lug struck up from the other plate. 45

3. A ticket roll clip formed of thin sheet metal and comprising a slotted plate and a tongue bearing plate, respectively, arranged in superimposed relation and of substantially equal lengths transversely of a ticket 50 strip width, with the tongue of one plate engaging the slot of the other plate for limiting the reciprocal adjustment of said plates, each of said plates having inturned spurs to pierce the sides of the ticket roll 55 to hold the clip secure thereon.

4. A ticket roll clip comprising a retaining member embodying slidably, superposed, sheet metal sections adapted to straddle over the loose end of a ticket strip, each of 60 a length substantially the width of a ticket strip, one of said sections having a slot and the other section having a tongue slidable in said slot and serving to limit the relative 65 adjustments of the two sections, depending flanges on the free margins of said sections for engaging the sides of a ticket roll, and clip securing means integral with said flanges and penetrating the sides of the 70 roll when the sections are adjusted inwardly to embrace the roll.

In testimony whereof I affix my signature.

JAMES M. MONTGOMERY.
